CONVERTIBLE SEWING AND DARNING
MACHINE

Richard K. Hohmann, Jamaica, and Frederick Osann, White Plains, N. Y., assignors to Sears, Roebuck and Co., Chicago, Ill., a corporation of New York

Application December 29, 1939, Serial No. 311,486

12 Claims. (Cl. 112—121)

The general object of our present invention is to provide a simple and effective sewing machine adapted for interchangeable use as a darning machine and for ordinary sewing operations.

One specific object of the invention is to provide a sewing machine which is readily convertible from one to the other of two conditions in one of which it is adapted for plain sewing and includes a flat work bed, which may be generally similar in form and disposition to the conventional work bed of a plain sewing machine, and in the other of which it is adapted for darning and is adapted to support stockings or other work to be darned, on a cylinder arm generally like, though preferably somewhat smaller in cross section than, the work supporting cylinder arms of ordinary darning machines. In its preferred form, the machine is adapted, however, for either plain sewing or darning operations, on flat bed and cylinder arm supported work.

Another specific object of the invention is to provide a sewing machine of the kind specified with a presser bar mechanism readily adjustable between a plain sewing condition in which the presser foot continuously engages the work, and a second darning condition in which the pressure bar is lifted between successive needle strokes.

Another specific object of the invention is to provide a presser bar actuating mechanism adjustable to give the presser bar relatively low lift movements suitable for darning stockings or other thin material, and relatively high lift movements needed in darning blankets or other thick material.

Another specific object of the invention is to provide a novel work feed mechanism, especially adapted for use in a sewing machine in which all of the underbed sewing instrumentalities are located in a hollow cylinder arm of relatively small cross section.

Another specific object of the invention is to provide a pulley and belt drive connection between a driving pulley mounted on the needle bar shaft and a driving electric motor located in the base of the sewing machine, and including provisions by which the portion of the belt above the base of the machine is normally enclosed within the standard and adjacent arm portion of the machine, but may be made readily accessible for belt removable and replacement operation.

The various features of novelty which characterize the present invention are pointed out with particularity in the claims annexed to and forming a part of this specification. For a better understanding of the invention, however, its ad-

vantages and specific objects attained with its use, reference should be had to the accompanying drawings and descriptive matter in which we have illustrated and described preferred forms of embodiment of the present invention.

Of the drawings:

Fig. 1 is an elevation, partly in section, of a sewing machine constituting a preferred embodiment of the present invention;

Fig. 2 is an enlarged reproduction of a portion of Fig. 1, showing parts in different relative positions;

Fig. 3 is a section on the line 3—3 of Fig. 1 with parts broken away and removed;

Fig. 4 is an elevation on the plane indicated by the line 4—4 of Fig. 1, of the sewing machine head with its front cover plate removed;

Fig. 5 is a section on the line 5—5 of Fig. 4; showing the presser bar lift adjusting provisions in one position;

Figs. 6 and 7 are sections taken similarly to Fig. 5, showing said adjusting provisions in different positions;

Fig. 8 is a perspective view of the presser bar lifting and lift adjusting provisions;

Fig. 9 is a plan partly in section on the line 9—9 of Fig. 1;

Fig. 10 is a section on the line 10—10 of Fig. 1;

Fig. 11 is a partial section on the broken line 11—11 of Fig. 10;

Fig. 12 is a partial section on the line 12—12 of Fig. 10;

Fig. 13 is a composite perspective view showing different work feeding mechanism parts;

Fig. 14 is a perspective view illustrating details of the main pulley mounting;

Fig. 15 is a small scale elevation of a removable cover plate at the right hand end of the machine as shown in Fig. 1;

Fig. 16 is a perspective view of the removable flat bed part shown in Fig. 1;

Fig. 17 is a perspective view showing parts of the cylinder arm and flat work bed of Fig. 1 in section;

Fig. 18 is a view taken similarly to Fig. 17, illustrating the use of a flat work bed member of modified form; and

Fig. 19 is a perspective view of the removable flat work bed member shown in Fig. 18.

The housing structure, or framework of the sewing machine illustrated in the drawings comprises a rectangular supporting bottom plate A, and a sewing machine framework proper which is screw connected to the bottom plate and includes a rectangular base or bed portion A', a standard

A^2 , and a horizontal cylinder arm comprising a portion A^5 and A^6 . The portion A^6 is an integral tubular extension of the base portion A' and A^6 is a tubular part detachably secured to the front end of the part A^6 and forming an extension of the latter.

The machine comprises a driving motor B , mounted in the base portion A' and having a pulley B' on its shaft which is operatively connected by a belt C to a driving pulley D mounted on the adjacent end of the needle bar shaft E , which may be journaled in the arm A^3 in any usual or suitable manner. In the preferred construction shown, the rear end E' of the needle bar shaft E is threaded, and supports a nut member F , which may be rotated about the shaft end E' to thereby clamp the hub portion of the pulley D between the head of the nut member F and the radially extending flange of a part E^2 carried by and secured to the shaft E and comprising a tubular hub portion E^3 forming an elongated bearing for the pulley D . When the nut F is backed off, as shown in Fig. 2, the pulley E may be displaced axially of the shaft E , from its normal position, to thereby move the inner, belt groove portion of the pulley out of its normal position within the arm A^3 so as to permit the belt C to be removed from and replaced on said pulley. As shown, a washer member F' is interposed between the nut F and the hub of the pulley D , said washer member having integral arm extensions F^2 received in longitudinal slots formed for the purpose in the tubular portion E^3 of the part E^2 .

At its head end, the shaft E carries a crank disc E^4 in which is mounted a crank pin E^5 connected by a link G' to a pivot pin G^2 carried by the needle bar G , mounted in the head A^4 in any usual or suitable manner for vertical reciprocatory movement. The needle bar G also carries a cam roller G^3 , which, on each up movement of the needle bar, gives a counterclockwise movement to a bell crank lever H pivoted to turn about a horizontal pivot H^0 and spring biased for counterclockwise movement as the needle bar descends. The horizontal arm of the bell crank lever H comprises uprising projections H' and H^2 at lesser and greater distances respectively, from the axis of the lever H . On each needle bar upstroke, one, or the other, or neither, of the projections H' and H^2 is adapted to operatively engage the vertically movable presser bar h depending on the angular adjustment of a member h^a mounted on, and rotatable about the presser bar h . The bar h is normally biased for down movement by a spring h' .

A lever HA extending into the head A^4 and pivotally connected through a pivot HA' , has a bifurcated lower end straddling a pin h^3 depending from the upper portion of the member h^a , and laterally displaced from its axis, so that the member h^a may be angularly adjusted by angular adjustment of the lever HA . The latter has an operating portion external to the head A^4 provided with a latching part HA^2 through which the lever HA may be anchored in its different positions relative to the head required to hold the part h^a in its different positions shown in Figs. 5, 6 and 7. The member h^a comprises arms h^4 and h^5 .

In the angular adjustment of the member h^a shown in Fig. 7, its arm h^4 is in position to be engaged and lifted by the projection H^2 and thereby give a "high" lift to the presser bar, such as may be needed in darning blankets. In a sec-

ond angular adjustment of the member h^a , shown in Fig. 6, its portion or arm h^5 is in position to be engaged and given a low lift, suitable for stocking darning, by the projection H' , the arm h^4 then being out of position for engagement by the projection H^2 . In the third adjustment of the member h^a , suitable for plain sewing and shown in Fig. 5, neither of the arms h^3 and h^4 is in position for engagement by the corresponding projection H' or H^2 , and clockwise movements of the lever H will not lift the presser bar.

When the member h^a is given an up movement by the lever H , that up movement is normally transmitted to the presser bar h through the engagement of the upper end of the member h^a with an abutment member h^6 clamped on the presser bar, and normally held by the spring h' in engagement with part h^a , in all positions of the latter. A second member h^7 , also clamped on the presser bar, extends through a slot in the side wall of the head A^4 , and thus serves as the guide preventing angular movement of the presser bar. As shown in Fig. 4, a manually adjustable cam lever HB is in the position in which it engages the part h^7 and holds the presser bar in an elevated position slightly above the high lift position into which it may be moved by the projection H^2 and arm h^4 of the member h^a . In the normal position of the lever HB , shown in dotted lines in Fig. 4, it permits the part h^6 to bear on the member h^a in all positions of the latter.

The sewing machine includes tension and thread takeup provisions which may be of conventional type and hence not requiring description herein.

The sewing machine mechanism shown, is of the rotary hook type, and comprises a hook shaft I , which is suitably journaled in the frame part A' and its cylinder arm extension A^5 , and which carries a loop taker or hook element i adjacent the front end of the machine. The hook shaft I is rotated by the needle bar shaft E through a vertical shaft I' journaled in the standard A^2 and having its upper end connected to the shaft E by bevel gears I^{22} and having its lower end connected to the hook shaft I through bevel gears I^3 . Desirably, and as shown, the gears are so proportioned that the shaft I will rotate with double the angular velocity of the shaft E .

The sewing machine includes work feeding means comprising a feed dog K adapted to extend up into and to move horizontally in the slot of a throat or needle plate part KA , of conventional flat form and supported by the cylinder arm part A^6 . The work feeding means also comprises mechanism within the hollow cylindrical arm of the sewing machine for giving the feed dog its feeding movements. Said mechanism comprises a cross head member L mounted in a guideway M' in a second cross head M for vertical movement relative to the latter. The feed dog K is normally secured to the upper end of the member L by screws. The feed dog support L is given up and down movements by the angular oscillation of a shaft L^5 , which carries an arm including a portion L^6 parallel to, but laterally displaced from the shaft L^5 , and entering a horizontal slot formed in the upper portion of the member L .

In the preferred construction shown, the shaft L^5 is tubular and surrounds an oscillating shaft M^5 which carries at its front end a crank arm M^6 supporting a pin M^7 parallel to and laterally displaced from the shaft M^5 . The pin M^7 enters a

suitably formed opening M^8 in the member M , which is mounted in the framework of the machine for horizontal-to-and-fro movement in a direction transverse to the needle bar shaft and to the shafts M^6 and L^5 . The mounting provisions illustrated comprise stationary guide pin parts M^9 and M^{10} , respectively received in slots M^{11} and M^{12} , formed in the opposite sides of the member M . Through the arm M^6 and pin M^7 , the oscillatory movements of the shaft M^5 thus give horizontal movements to the member M , and thereby to the member L and to the feed dog K carried by the latter. Through the pin L^6 the oscillatory movements of the tubular shaft L^5 give vertical movements to the member L in the guideway M' of the member M . As shown, the pin L^6 extends through a slot M^{13} in the upper portion of the member M , so shaped and disposed as to accommodate the oscillatory movements of the pin L^6 . Each of the members L and M is formed with an opening for the passage of the hook shaft E large enough to accommodate the movements of the parts L and M relative to that shaft.

The shaft M^5 is oscillated to give the feed dog K its horizontal feeding movements, through a crank arm M^{20} secured to the rear end of the shaft M^5 and an actuating lever M^{21} pivotally connected to the arm M^{20} . The lever M^{21} has an upper end straddling a cam carried by the shaft E . A roller M^{22} pivotally connected to the lever M^{21} is received in the guideway in a member M^{23} which is pivotally connected to the standard A^2 and is provided with a stitch adjusting arm M^{24} extending through a slot in the side of the standard A^2 , so that the member M^{23} may be adjusted angularly in one direction away from a position in which the guideway extends horizontally, into positions in which it is inclined upwardly away from the horizontal position, and in the other direction into other positions in which it is inclined downwardly away from the horizontal.

With the guideway in the member M^{23} horizontally disposed, the oscillatory movements given by the shaft E to the upper end of the lever M^{21} will impart no oscillatory movement to the lower end of the lever M^{21} or to the shaft M^5 . When the free end of the arm M^{23} is moved downward to incline the guideway downwardly from the horizontal, the feed dog K will be given feeding movements in the normal direction, i. e., away from the user of an extent varying with the inclination of the guideway to the horizontal. When the free end of the lever is raised, and the guideway is inclined upwardly away from the horizontal, the oscillatory movements given to the upper end of the lever M^{21} will impart back feed movements to the feed dog K , of a magnitude depending on the inclination of the guideway to the horizontal.

The shaft L^5 is given oscillatory movements and the feed dog K thereby given up and down movements through an arm L^{20} secured to the rear end of the tubular shaft L^5 and pivotally connected to the lower end of a link L^{21} which, on its upper end, carries an eccentric strap L^{22} surrounding an eccentric on the shaft E .

The means including the angularly adjustable guide member through which the movements imparted by the shaft E to the upper end of the lever M^{21} give the feed dog K feeding movements in the normal direction, or in the reverse direction, or hold the feed dog against horizontal movement, are of a known type. The feed mechanism illustrated and described, is believed to be novel

in its general organization, however, and is especially adapted for use as shown with the bulk of the feeding mechanism located within a cylinder arm of small cross section.

As shown in Fig. 3, the shaft of the motor B is parallel to the needle bar shaft E and hook shaft I , but is laterally displaced from the latter. To accommodate this displacement without requiring the standard A^2 to have an unconventional and undesirable form, an idler pulley N , normally engaged by the rear run of the belt, is so located as to deflect the lower portion of that belt run into or near parallelism with the belt front run which extends in a direction inclined to the vertical from the pulley B' to the pulley D . In the normal operating position, the upper portion of the belt groove in the pulley D is within and closely encircled by a cylindrical portion A^{10} of the framework. An opening 20 formed in the standard A^2 and base member A' , at the right hand end of the machine, as seen in Fig. 1, is normally closed by a removable cover plate or member A^{11} , shown in outline in Fig. 15. The removal of the cover member A^{11} gives access 25 to the portion of the belt and other mechanism within the hollow standard.

In the form shown in Fig. 1, the sewing machine includes a removable work bed member P , shown in perspective in Fig. 16. As shown in Figs. 1 and 16, the latter is in the form of a metal box minus its bottom wall and open at its end which, when the part is in use as shown in Fig. 1, is adjacent and bears against the sewing machine frame part A' . The part P is formed with an opening P' in its top wall to receive the throat plate member KA and with an adjacent opening P^2 partly in the top wall and partly in the closed end member. The opening P^2 is normally closed by a hinged cover member P^3 , which when moved into open position, permits access to the bobbin case extending into the loop taker, for insertion and removal of bobbins. As shown, the base plate A is formed with an uprising marginal flange AA in telescopic engagement with the lower portion of the bed plate part P , whereby the latter is anchored in position. With the part P in place, the machine as a whole, has the general appearance and operative capacity of an ordinary flat bed sewing machine. With the bed member P removed, the work support is of the cylinder arm form heretofore used in darning stockings and other work. As shown in Fig. 17, the tubular cylinder arm may advantageously be generally elliptical in cross section but with its top portion flattened to provide a flat seat for the engaging top wall portion of the member P .

In lieu of the flat work bed part P shown in Figs. 1, 16 and 17, I may make use of the work bed part PA shown in Figs. 18 and 19. The part PA differs from the part P in that it is formed with a longitudinal slot P^{10} in its top wall adapted to receive the flattened top wall portion of the cylinder arm A^{10} , which to this end may differ in shape from the cylinder arm first described, in that its top wall portion is in the form of a flat rib shaped to fit into the slot P^{10} .

As shown, a bobbin winder wheel Q , carried by an arm Q' pivotally connected to the standard A^2 , is adapted to be turned from its idle position, shown in Fig. 3 into the position in which the wheel Q extends through a slot formed for the purpose in the standard A^2 , and frictionally engages the pulley D , which, during the bobbin winding operation is normally free to turn on the needle shaft E .

The general operation of the sewing machine illustrated and described, will be readily apparent to those skilled in the art. With either of the bed plate parts P and PA in place, and with the thrust member h^a out of position for operative engagement by the oscillating lever H, and with the member M^{26} adjusted through its arm M^{26} into position to effect the desired work feeding movements of the feed dog K, the machine will operate as an ordinary plain sewing machine. When the thrust member h^a is adjusted into position for operative engagement by the oscillating lever H, and the guide member M^{25} is adjusted by the arm M^{26} into position to render the feed mechanism inoperative, the machine is adapted for operation like an ordinary darning machine. By adjusting the member h^a to vary the distance from the vertical plane including the axis of the lever H at which the lever operatively engages the member h^a , the extent of lift given the presser bar may be varied in conformity with the character and particularly the thickness of the work. In the plain sewing mode of operation, the position of the work is controlled by two elements, namely, by the presser foot which continuously engages the work and holds it in position for intermittent engagement by the feed mechanism, which constitutes the second of said elements. In the contemplated darning mode of operation, the work is free from position control by either of the above mentioned elements during an interval between each two successive penetrations of the work by the needle, but the presser foot operatively engages the work at the beginning of, or before, each penetration of the work by the needle.

As previously stated, the machine may be used interchangeably in plain sewing and darning operations, either with the flat bed part P or PA in place, or removed so that the work may be supported on the cylinder arm. The flat bed parts P and PA are simple in form and easily put in place and removed. In some operations, for example, in repairing a child's sleeve or pant leg which has a rip running into a hole, our improved machine may effect the plain sewing and darning portions of the repair operation needed, one after the other, without any interruption of the reciprocatory movements of the needle, and without any adjustment of the work relative to the cylinder arm work support, other than the automatic advancement of the work by the feed mechanism in sewing up the rip, and the manual adjustment of the work during the darning operation effected after the levers HA and M^{26} have been adjusted to respectively subject the presser foot to the lifting action of the lever H, and to interrupt the horizontal movement of the feed dog K. The driving connection between the motor and the needle shaft is relatively simple, and the belt removal and replacement operations are simple and of a character to be readily performed by the ordinary housewife. The sewing machine shown is of the portable type, but our improvements disclosed and claimed herein are adapted for use in sewing machines of the cabinet type, or of the convertible cabinet and portable type disclosed in the copending application Ser. No. 313,507, filed January 12, 1940, by Richard K. Hohmann, one of the petitioners herein. Novel features of construction and arrangement disclosed but not claimed herein are claimed in one or another of our divisional applications Serial No. 348,928, filed July 13, 1940, Serial No. 351,013, 75

filed August 3, 1940, and Serial No. 351,014, filed August 3, 1940.

While in accordance with the provisions of the statutes, we have illustrated and described the best form of embodiment of the invention now known to us, it will be apparent to those skilled in the art that changes may be made in the form of the apparatus disclosed without departing from the spirit of the invention as set forth in the appended claims and that in some cases certain features of our invention may be used to advantage without a corresponding use of other features.

Having now described our invention, what we claim as new and desire to secure by Letters Patent, is:

1. A sewing machine adapted for interchangeable use in plain sewing and darning operations and including in combination a frame, and mechanism mounted in said frame and comprising needle reciprocating means, cooperating stitch forming mechanism, feed mechanism, means to make said feed mechanism operative or inoperative, a presser foot above said feed mechanism, and means controlling the position of said presser foot and selectively operable to maintain said presser foot in position to continuously engage work interposed between said presser foot and feed mechanism, or to operatively connect said presser foot to said needle reciprocating means and thereby cause said presser to be lifted out of its work engaging position in synchronism with the reciprocatory movements of the needle.

2. A sewing machine adapted for interchangeable use in plain sewing and darning operations and including in combination a frame, and mechanism mounted in said frame and comprising needle reciprocating means, cooperating stitch forming mechanism, feed mechanism, means to make said feed mechanism operative or inoperative, a presser foot above said feed mechanism and biased for continuous engagement with work interposed between said presser foot and feed mechanism, lifting means adapted, when operative, to lift said presser foot out of and permit it to return into engagement with the work in synchronism with the needle movements, and means for rendering said lifting means inoperative.

3. A sewing machine adapted for darning operations and comprising in combination a frame and mechanism mounted therein and comprising a needle reciprocating means, cooperating stitch forming mechanism, a presser bar and foot having a thrust surface, and means adapted to lift said presser foot out of and return it into its work engaging position in synchronism with the reciprocatory needle movements comprising a lever arm pivoted to said frame to turn about a horizontal axis and operatively engaged by said needle reciprocating means to oscillate said lever arm about said axis in timed relation with the reciprocatory movements of the needle, and thrust means interposed between said lever arm and thrust surface through which said lever arm engages and lifts said presser bar, said thrust means including adjusting means operable to vary the leverage with which said lever arm acts on said thrust surface.

4. A sewing machine as specified in claim 3, in which said thrust means comprises a member mounted on the presser bar and angularly adjustable about said bar to thereby vary the said leverage.

5. A sewing machine adapted for interchange-

able use in plain sewing and darning operations and including in combination a frame and mechanism mounted in said frame and comprising needle reciprocating means, cooperating stitch forming mechanism, feed mechanism, means to make said feed mechanism operative or inoperative, a presser bar having a presser foot and biased for continuous engagement of said foot with the work, a lever actuated by the needle reciprocating means to oscillate in synchronism with the needle movements about a horizontal axis, and a thrust member mounted on said presser bar for angular adjustment about the latter into one position in which it is engaged by said oscillating lever at a predetermined distance from said axis to give relative high lifting movements to said presser bar, and into a second position in which said member is engaged by said oscillating lever at a distance from said axis less than the first mentioned distance to give relatively low lifting movements to said presser bar.

6. A sewing machine adapted for interchangeable use in plain sewing and darning operations and including in combination a frame, and mechanism mounted in said frame and comprising needle reciprocating means, cooperating stitch forming mechanism, feed mechanism, means to make said feed mechanism operative or inoperative, a presser bar having a presser foot and biased for continuous engagement of said foot with the work, a lever actuated by the needle reciprocating means to oscillate in synchronism with the needle movements about a horizontal axis, and a thrust member mounted on said presser bar for angular adjustment about the latter into three predetermined, different positions, and adapted in one position to be engaged by said oscillating lever at one distance from said axis to thereby give relative high lifting movements to said presser bar, and in a second of said positions to be engaged by said oscillating lever at a distance less than the first mentioned distance from said axis and thereby gives relatively low lifting movements to said presser bar, and when in the third position being out of operative engagement with said lever, so that the oscillations of the latter do not then lift the presser bar.

7. A sewing machine as specified in claim 1, in which the said means selectively operable to control the position of said presser foot comprises an actuating lever pivoted on said frame and accessible for ready adjustment by the sewing machine user to predetermined angular positions.

8. A sewing machine adapted for darning operations and including in combination a frame and mechanism mounted in said frame and comprising needle reciprocating means, cooperating stitch forming mechanism, a presser bar having a thrust surface and a presser foot and means adapted to lift said presser foot out of and return it into its work engaging position in synchronism with the reciprocatory movements comprising a lever arm pivoted to said frame to turn about a horizontal axis displaced laterally from the presser bar, and operatively engaged by said needle reciprocating means and thereby oscillated

about said axis in timed relation with the reciprocatory movements of the needle, and thrust means interposed between said lever arm and thrust surface through which said lever engages and lifts said presser bar, said thrust means including means to vary the lateral distance between the vertical plane including said axis and the point at which said member is engaged by said lever arm.

10. 9. A sewing machine as specified in claim 1 in which the said means selectively operable to control the position of said presser foot comprises an actuating lever pivoted on said frame and accessible for ready adjustment by the sewing machine user to predetermined angular positions and positioning means associated with said lever and determining the different angular positions of the lever and tending to maintain the latter in each of said positions into which it is adjusted.

15. 10. A sewing machine as specified in claim 1, in which the said means to make said feed mechanism operative or inoperative, comprises an actuating lever pivoted on said frame and accessible for ready adjustment by the sewing machine user to render said feed mechanism operative or 20. 25. 30. 35. 40. 45. 50. 55. 60. 65. inoperative, and in which the said means controlling the position of the presser foot comprises an actuating lever accessible for ready adjustment by the sewing machine user to predetermined angular positions.

11. A sewing machine adapted for interchangeable use in plain sewing and darning operations and comprising in combination a frame including a standard, overhanging arm and needle head, a vertically reciprocating needle bar mounted in said head, a presser bar mounted in said head back of said needle bar and having a thrust surface, a lever at the side of said bars remote from said standard and pivoted to said frame to turn about a horizontal axis parallel to said arm and in front of said presser bar, means carried by said needle bar engaging said lever and oscillating the latter on each reciprocation of the needle bar, and a member adjustable into and out of an operative position in which it forms a thrust connection between said lever and presser bar thrust surface lifting the presser bar on each oscillation of the lever.

12. A sewing machine adapted for interchangeable use in plain sewing and darning operations and comprising in combination a frame including a standard, overhanging arm and needle head, a vertically reciprocating needle bar mounted in said head, a presser bar mounted in said head back of said needle bar, and having a thrust surface, a lever at the sides of said bars remote from said standard and pivoted to said frame to turn about a horizontal axis parallel to said arm and in front of said presser bar, means carried by said needle bar engaging said lever and oscillating the latter on each reciprocation of the needle bar, a member forming a thrust connection between said thrust surface and lever, and adjustable between two positions in which said lever respectively engages said member at greater and lesser distances from said axis.

RICHARD K. HOHMANN.
FREDERICK OSANN.
